UNITED STATES PATENT OFFICE.

EDWARD J. TRIMBEY, OF GLENS FALLS, NEW YORK.

REGULATING APPARATUS.

1,178,194.

Specification of Letters Patent. Patented Apr. 4, 1916.

Application filed September 15, 1915. Serial No. 50,789.

To all whom it may concern:

Be it known that I, EDWARD J. TRIMBEY, a citizen of the United States, residing at Glens Falls, Warren county, State of New York, have invented certain new and useful Improvements in Regulating Apparatus; and I do hereby declare the following to be a full, clear, and exact description of the invention, such as will enable others skilled 10 in the art to which it appertains to make and use the same.

In the present state of the art of paper making there is no rapid method of determining the per cent. consistency of the wet 15 pulp as it is pumped to the beaters or to the mixing tanks, or of wet paper stock as it is pumped to the head-box of the paper machine or of the Jordan engine where it is to be further refined. Such pulp or paper 20 stock commonly consists of about three to five parts of bone-dry matter in one hundred parts of wet pulp or wet paper stock, and such percentage of bone-dry matter is commonly referred to as the per cent. consistency.

The present invention relates to a stuff meter or regulating apparatus for determining and regulating the per cent. consistency of the pulp or paper stock in a convenient 30 and rapid manner; so that by inspection, the consistency of the pulp or paper stock can be determined and the amount of water which must be added to dilute the same to a predetermined lower consistency, also readily determined, and the regulation of the pulp consistency thereby effected.

It is important in the manufacture of paper, that the pulp or paper stock should have the proper consistency, and that, when 40 the pulp or paper stock is too thick, the proper amount of water should be added, so that the pulp or paper stock shall be of uniform consistency, and the resulting paper of uniform weight per unit area.

45 The invention will be described more particularly in connection with the regulation of pulp, inasmuch as regulation of paper stock is effected in substantially the same manner, but it will be understood that the term pulp, when thus referred to, is used with a more general signification.

The novel apparatus of the present invention is similar to that of my Patent No. 1,161,168, granted November 23, 1915, and 55 comprises, briefly, a constant level chamber

having a discharge orifice maintained under a constant head of the pulp or paper stock, and a variable level chamber arranged to receive the pulp or paper stock discharged from said orifice and provided with an outlet pipe of suitable size and proportion to cause a frictional resistance to the flow of the pulp or paper stock therethrough, and thereby maintain a head of the pulp or paper stock within the chamber varying with its consistency and frictional resistance. The present invention is distinguished from that of said prior application in that the variable level chamber is yieldably supported, and is provided with indicating means, operated by the movements of the chamber, for indicating the pulp or paper stock consistency, and the dilution necessary to give a predetermined lower consistency.

I will now proceed to describe my invention more in detail with reference to the construction illustrated on the accompanying drawings, in which—

Figure 1 shows, partly in elevation and partly in section, an arrangement of apparatus embodying the invention; Fig. 2 is a top view of part of the apparatus of Fig. 1; and Fig. 3 is another top view of another part of the apparatus of Fig. 1.

In the construction illustrated, the constant level chamber 1 is provided with an overflow dam or partition 2 dividing the same into two compartments 3 and 4. The compartment 3 is provided in its bottom 85 with an opening 5 covered with a thin sheet of metal having therein a discharge orifice 6. A supply pipe 7 for the pulp or paper stock enters the compartment 3, this flow being regulated by a suitable valve 8. The supply pipe 7 is shown as a branch leading from the main supply pipe 9 through which the pulp or paper stock is fed to the paper machine or to other suitable place of use or of further treatment. A suitable circulating pump is indicated at 10, and a regulable water supply pipe at 12, the main stuff chest being indicated at 11. From the compartment 3 the excess pulp overflows into the compartment 4 and is returned by means of 90 the pipe 13 to the stuff chest 11. A suitable 100 circulating pump is indicated at 10, and a regulable water supply pipe at 12, the main stuff chest being indicated at 11. From the compartment 3 the excess pulp overflows into the compartment 4 and is returned by means of 105 the pipe 13 to the stuff chest 11.

Positioned below the discharge orifice 6 is a variable level chamber 14 provided with a restricted outlet pipe or spout 15 discharging at 16 into the branch 17 of the return 110

pipe 13 leading to the stuff chest 11. The outlet of this variable level chamber is of a suitable size and proportion to cause a frictional resistance to the passage of the pulp therethrough and thereby maintain a head of pulp within the chamber varying with the pulp consistency. The variable level chamber 14 is yieldably supported on an arm 18 pivoted at 19 to the support 20. The arm 18 has a counter-weight 21 and is connected at its end at 22 by a yielding connection to the support 27 at 23. The yielding connection is indicated as a member 24 having therein a suitable spring, and also having 15 two scales 26 with which a pointer 25 operates.

In the operation of the apparatus, a suitable portion of the pulp or paper stock is drawn off by the branch pipe 7 from the 20 main supply pipe 9, and is introduced into the bottom of the compartment 3. The excess pulp overflows the partition 2 and returns to the stuff chest, thereby maintaining a constant head within the compartment 3. From the bottom of this compartment the pulp is discharged under this constant head into the variable level chamber 14. The rate of flow into this second chamber is determined by the size of the 25 orifice 6, and is relatively constant owing to the constant head and to the minimum of frictional resistance offered to the passage of the pulp through the thin orifice. The head within the chamber 14 is largely controlled by the frictional resistance opposing 30 the flow of the pulp or paper stock through the outlet therefrom. This frictional resistance will vary with the per cent. consistency of the pulp or paper stock, the head increasing 35 with the increase in consistency until it is sufficient to overcome the frictional resistance. The level of the pulp will accordingly indicate the consistency of the pulp and the amount of water which must be 40 added to dilute it to a predetermined lower consistency.

In the construction illustrated, the head of pulp or its level within the chamber 14, is indicated by the pointer 25 upon the scale 50 26. The counter-weight 21 can be adjusted to overcome the weight of the chamber 15 and its contained pulp or paper stock when such pulp or paper stock is of the desired consistency. Any increase in consistency 55 will cause an increase in the head within the chamber 14 with resulting increase in weight, this increase in weight being due to the increase in head.

When using this apparatus, it is advanced 60 tageous to have the pulp in the supply chests at a somewhat higher consistency than it is desired to maintain at the head box of the paper machine or in the beaters or mixing tanks, and to add a suitable amount of water 65 for thinning to the proper consistency; for,

while the wet pulp or wet paper stock can be easily diluted if of a too high consistency, it cannot be readily thickened if too dilute.

As it is the general practice to use a head-box in which a constant level is maintained, 70 for regulating the supply of the pulp or paper stock to the paper machine or to the Jordan engine, the orifice 6 can be located in the bottom of the regular head-box in such cases. Such head-boxes will accordingly 75 correspond to the box or constant level chamber 1, illustrated.

It will be seen that the discharge through the orifice 6 is relatively constant, inasmuch as this discharge takes place under a constant head. Such slight variations as may occur in practice do not interfere with the satisfactory operation of the apparatus. It will also be seen that the discharge spout 15 of the chamber 14 is of considerable length 80 so that a considerable frictional resistance is offered to the passage of the pulp therethrough, this resistance increasing with increase in the pulp consistency, and vice versa. The increase in head of pulp, and consequently in level within the variable level chamber 14, will be indicated upon the scale 26 by the pointer 25. Two scales are shown, one of which is calibrated in terms of the 85 pulp consistency, and the other in terms of the water which must be added to give the proper dilution. Accordingly, with the apparatus of the present invention, the operator can continually observe the consistency of the pulp, as indicated on the calibrated 90 scale, and can also determine by inspection the amount of water which must be added to give the proper dilution. Complete control of the pulp consistency is thus provided 100 for, so that the operator can readily regulate the water supply in accordance with the consistency of the pulp and thus obtain a paper of uniform weight per unit area.

While the invention has been described more particularly in connection with the embodiment thereof illustrated in the accompanying drawings, yet it will be understood that variations and modifications can be made therein without departing from the spirit and scope of the invention as set forth 115 in the accompanying claims.

What I claim is:—

1. A regulating apparatus for wet pulp and wet paper stock, comprising a constant level chamber having a discharge orifice maintained under a constant head of the pulp or paper stock, a yieldably supported variable level chamber arranged to receive the pulp or paper stock discharged from said orifice and provided with an outlet pipe of suitable size and proportion to cause a frictional resistance to the flow of the pulp or paper stock therethrough, and thereby maintain a head of the pulp or paper stock within the chamber varying 125

120

125

130

- with its consistency and frictional resistance, and means in connection with said yieldable support for indicating variations in the head of the pulp or paper stock in 5 said chamber; substantially as described.
2. A regulating apparatus for wet pulp, and wet paper stock, comprising a constant level chamber having a discharge orifice maintained under a constant head of 10 the pulp or paper stock, a yieldably supported variable level chamber arranged to receive the pulp or paper stock discharged from said orifice and provided with an outlet pipe of suitable size and proportion to 15 cause a frictional resistance to the flow of the pulp or paper stock therethrough, and thereby maintain a head of the pulp or paper stock within the chamber varying with its consistency and frictional resistance, said 20 yieldable support being provided with a scale and pointer for indicating variations in the head of the pulp or paper stock and corresponding variations in the consistency thereof; substantially as described.
- 25 3. In a regulating apparatus, a variable level chamber comprising an enlarged upper portion and a relatively smaller discharge portion extending downwardly therefrom and terminating in an upwardly 30 extending discharge neck, said discharge portion and neck being of suitable size and proportion to cause a frictional resistance to the flow of the pulp or paper stock there-
- through, and thereby maintain a head of the pulp or paper stock within the upper 35 portion of the chamber varying with its consistency and frictional resistance; substantially as described.
4. A regulating apparatus for wet pulp and wet paper stock, comprising a constant 40 level chamber having a discharge orifice maintained under a constant head of the pulp or paper stock, a pivotally supported variable level chamber arranged to receive the pulp or paper stock discharged from 45 said orifice and provided with an outlet pipe of suitable size and proportion to cause a frictional resistance to the flow of the pulp or paper stock therethrough, and thereby maintain a head of the pulp or paper stock within the chamber varying with its consistency and frictional resistance, a 50 support for said variable level chamber, a supporting arm to one end of which said chamber is pivoted, a counter-weight upon the other end of said arm, and a yielding connection arranged between said arm and support provided with a scale and pointer for indicating variations in the head of the pulp or paper stock and corresponding variations in the consistency thereof; substantially as described. 55
- 60 In testimony whereof I affix my signature.

EDWARD J. TRIMBEY.
